FLOODLIGHT UNIT

Royal E. Crossley, Fayetteville, N. Y., assignor to
Crouse-Hinds Company, Syracuse, N. Y., a corporation of New York

Application January 17, 1940, Serial No. 314,277

7 Claims. (Cl. 240—26)

This invention relates in general to a floodlight unit, and more particularly to a floodlight unit intended to be mounted in inaccessible locations making it difficult to relamp the unit or adjust the optical system thereof.

My invention is herein illustrated in the form of an underwater floodlight unit arranged to illuminate a swimming pool. Inasmuch as these units are mounted under water, it is extremely difficult to relamp the same. At the present time, there are two arrangements used for floodlights of this character. One arrangement is known as the wet niche installation in which the walls of the swimming pool are formed with niches into which a water tight lighting unit is arranged. This unit is provided with a long waterproof cord, and the arrangement is such that the unit may be bodily removed from the niche and taken to the surface, whereupon it may be disassembled to the extent necessary to permit replacement of the lamp. This arrangement is not satisfactory, inasmuch as it requires a well experienced swimmer to stay under water long enough to remove the unit and again replace it after it has been relamped.

In the second arrangement, or dry niche installation, the walls of the pool are formed with suitable openings closed by a lens mounted in water-tight relation in the face side of each opening. A sizeable trench, or series of manholes, are formed along each wall of the pool, and a lighting unit is mounted upon suitable brackets in this trench, or in the manholes, and each lighting unit is arranged in register with an opening in the wall. The trenches, or manholes, are of sufficient dimensions to permit a workman to relamp the units without removing them to the surface. This arrangement results in a very expensive installation because of the necessity of considerable additional excavation and the additional amount of concrete work involved.

There are other types of installations wherein the floodlight, or floodlight unit, is practically inaccessible. For example, on the ledges or parapets of office buildings and other building structures.

My invention has as an object a floodlight unit embodying a particularly simple and economical structure by which the unit may be quickly and conveniently relamped by a workman positioned a considerable number of feet from the unit.

The invention has as a further object a floodlight unit embodying a structure, as above referred to, including the provision of means

whereby the reflector of the unit may be adjusted as desired through a remote control mechanism of particularly simple and economical construction.

5 The invention consists in the novel features and in the combinations and constructions hereinafter set forth and claimed.

In describing this invention, reference is had to the accompanying drawings in which like characters designate corresponding parts in all the views.

Figure 1 is a vertical sectional view of a lighting unit embodying my invention with the reflector and other parts shown in elevation.

10 Figure 2 is a rear elevational view of the floodlight casing with a portion thereof broken away to show the reflector mounting.

Figure 3 is a vertical sectional view of the upper portion of the casing and contiguous parts 15 of the lamp receptacle assembly taken at substantially right angles to the sectional view in Figure 1, as indicated by line 3—3, Figure 5.

Figure 4 is a fragmentary sectional view of the upper portion of the lamp receptacle assembly 20 taken on line 4—4, Figure 5, and including the lower portion of the lamp receptacle assembly shown in elevation.

Figure 5 is a transverse sectional view taken on substantially line 5—5, Figure 1.

25 The invention comprises generally a casing which may be of any suitable size or form and which is provided with an aperture in one side. A tubular member is arranged in this aperture and extends outwardly. If desired, a reflector 30 may be mounted within the casing.

The unit further includes a lamp receptacle assembly including a lamp mounted in the receptacle, and which assembly is manually insertable through the tubular member, and means is provided for accurately positioning the lamp in the focal axis of the unit.

In the embodiment of the invention here shown, the casing consists of a rear bowl-like portion 10 and a forward cylindrical section 11, the two sections being formed with complementary flanges 12 which are secured together as by screws 13. A suitable lens 14 is secured in the outer end of the cylindrical section 11 to form a water-tight closure for the casing.

40 The casing is formed with an aperture 21 arranged in one side thereof and with a smaller threaded aperture to receive a drain pipe 22 to permit the escape of any moisture that may collect within the casing. A sleeve 23 is mounted in the aperture 21 as by cap screws 24. Preferably,

the aperture 21 is somewhat larger than the sleeve 23 to permit some adjustment of the sleeve about the screws 24 relative to the section 10 of the casing. The inner end of the sleeve 23 is formed with an annular portion 25 to which reflector supporting brackets 26 are secured, as by screws 27.

A tubular or pipe-like member 28 is arranged in the sleeve 23 and extends outwardly therefrom. When the unit is intended for underwater use, as for swimming pool illumination, the tubular member 28 is of sufficient length to extend within a short distance of the top surface 30 on the wall of the pool. Preferably, the upper end of the tube 28 terminates in an aperture formed in a housing 31 which is supplied with an electrical receptacle 32. For a swimming pool installation, it will be understood that the entire casing is arranged in the concrete wall 33, as is also the tubular member 28 and the upper housing 31. This installation is made by securing the casing in the form for the side wall of the pool, inserting the tubular member 28 in the sleeve 23, and mounting the housing 31 in the form for the top portion of the wall. Thereafter, the space between the aperture 21 and the sleeve 23, and the space between the upper end of the tube 28 and the aperture and housing 31 are filled with suitable caulking material, as at 37. Thereafter, the concrete is poured and these portions of the unit are securely fixed in the wall of the pool.

The lamp receptacle assembly comprises a lamp receptacle support which includes a plate 40 to which is adjustably secured a depending tube 41, to the lower end of which is secured a bracket 42. The plate 40, a plan view of which is shown in Figure 5, is circular in general form and of a diameter to permit the plate to be moved axially through the tubular member 28. The plate is formed with an upwardly extending boss 43 arranged to one side of the center thereof and with a transversely extending rib 44, and with a wall 45 connecting the boss 43 and rib 44. The wall 45 is formed with a central hub 46 threaded internally to receive a conduit 47 which serves as a stem or handle, whereby the lamp receptacle assembly may be manually manipulated.

The boss 43 is provided with a vertically, or axially, extending aperture to slidably receive the pipe or tube 41, the tube being secured in adjusted position by a set screw 48. A lamp receptacle 49 is secured to the bracket 42, and the bracket is provided with radially extending ears 50 which slidably engage the bore of the tube 28 to properly center the lower portion of the receptacle assembly, the upper portion being centered by the plate 40, as previously explained. The conduit 47 also serves to encase the cord 51, the outer end of which is provided with a plug 52 insertable in the receptacle 32 in housing 31, and the lower end of the cord is secured electrically to binding posts 54 mounted on plate 40. A suitable length of heat resisting cord 55 is connected at its upper end to the respective binding posts 54 and extends downwardly through the pipe 41 to the terminals of the lamp receptacle 49. Preferably, a cup-shaped washer 57 is slidably arranged upon the conduit 47, and is formed with a peripheral flange 58 engaging the upper end of the tube 28. The washer 57 serves to center the upper end of the conduit 47 when the lamp receptacle assembly is in operative position. The entire assembly is inserted in the casing by moving the same through the tubular member 28, the conduit 47 serving as a convenient stem or handle during this opera-

tion. The assembly descends in the tube 28 until the peripheral margin of the plate 40 engages the flange 25 of the sleeve 23. The tube 41 is adjusted relative to the plate at the factory to properly position the lamp 60 in the focal axis of the unit. The lamp is correctly positioned in a circumferential direction by means cooperable with the plate 40 during movement thereof through the tube 28.

As here shown, a rod 61 is secured in the flange 25 of the sleeve 23 and extends upwardly adjacent the side wall of the tube 28. The plate is formed with a recess 62 in the periphery thereof. Accordingly, the assembly can not be lowered into the casing until the recess 62 is in register with the rod 61. The top of the rod 61 is positioned a sufficient height above the flange 25 so that the plate 40 must be properly positioned circumferentially before the bracket 42 enters the casing.

With this construction, the lamp 60 is accurately positioned in the focal axis of the casing and of the reflector 63, if the unit is provided with a reflector. The reflector 63 is here shown as mounted in a transversely extending U shaped bracket 64, the ends of which are pivotally connected to the lower ends of the brackets 26, as by screws 65. The upper side of the reflector 63 is provided with an aperture of sufficient dimension to receive the lower end of the receptacle assembly, and the lower side of the reflector is provided with an aperture 66 to permit a portion of the lamp receptacle and one of the ears 50 to extend therethrough when the assembly is properly positioned.

In the event that the builder did not properly locate the casing in the concrete forms, or for any other reason it is desired to adjust the beam from the unit, the reflector 63 may be adjusted about its pivots 65. This is accomplished by a push-pull wire 67 mounted in a tube 68, the lower end of which is secured in the rear of the casing section 10, and the upper end of which extends into the housing 31. The upper end of the wire 67 is formed with a convenient finger loop 69, and the lower end is secured to the reflector bracket 64. Accordingly, the reflector can be tilted about the axis 65 by manipulation of the wire 67 in the housing 31.

The housing 31 may be provided with a removable cover 71. To relamp the unit, it is only necessary to remove the cover 71, remove the plug 52 from the receptacle 32, and pull the receptacle assembly out through the tube 28 using the stem 47 as a handle for the assembly. The lamp 60 may be then replaced and the assembly reinserted through the tube 28.

The structure of my invention avoids the necessity of diving under the water to remove the lighting unit, and of forming expensive manholes in the concrete walls of the pool. Obviously, the structure may be advantageously employed in floodlighting units arranged in inaccessible places on tall buildings and the like, in which event the tube 28 may be extended from the lamp and terminate in some position convenient to the workman. For outdoor installation, the tube 28 may be threaded, or otherwise secured directly to the casing 10.

What I claim is:

1. A floodlight unit comprising a casing formed with an aperture in one side thereof, a tubular member extending outwardly from said aperture, a lamp receptacle assembly including a lamp receptacle supporting plate, a lamp recep-

tacle carried by said plate, a lamp mounted in the receptacle, said assembly being insertable through said tubular member, a rod fixed relative to said casing and extending axially of said tubular member, said plate being provided with an aperture to slidably receive said rod, said rod being cooperable with said plate to guide the same in a predetermined relation to said casing during movement through said tubular member, and stop means operable to limit the axial movement of said plate.

2. A floodlight unit comprising a casing, a reflector pivotally mounted in said casing, said casing and reflector being formed with aligned apertures, a tubular member extending outwardly from the aperture of the casing, a lamp receptacle assembly including a lamp receptacle supporting plate, a lamp receptacle carried by said plate and a lamp mounted in said lamp receptacle, said lamp receptacle assembly being insertable through said tubular member and through the aperture in said reflector, said receptacle supporting plate being provided with a stem extending axially through said tubular member, stop means fixed relative to the casing and operable to limit the inward movement of said receptacle supporting plate, and guide means fixed relative to the casing and cooperable with said plate to guide the same in a predetermined relation to the casing during movement of the assembly through said tubular member, and motion transmitting means operatively connected to said reflector and extending in proximity to the outer end of said tubular member and being operable to move said reflector about its pivot.

3. A floodlight unit comprising a casing having an aperture in one side thereof, a tubular member extending outwardly from said aperture, a reflector arranged within said casing, a lamp receptacle assembly including a lamp receptacle supporting plate, a lamp receptacle bracket depending from said plate and being adjustable toward and from the same, a stem member for manual manipulation of said assembly extending outwardly from said supporting plate, guide means fixed relative to the casing and cooperable with said plate to guide the same in a predetermined relation to the casing during movement of the assembly through said tubular member, stop means operable to limit the inward axial movement of said assembly, and means carried by said receptacle bracket and cooperable with said tubular member to center the lower end of said assembly in said tubular member while said assembly is being moved through said tubular member.

4. A floodlight unit of the type described comprising a casing formed with an aperture in one side thereof, a tubular member arranged in the aperture of the casing and extending outwardly therefrom, a lamp receptacle assembly including a receptacle supporting plate adapted to be slidably moved through said tubular member, a lamp receptacle mounted upon the under side of said plate, a stem secured at one end to the upper side of said plate and extending axially through said tubular member and being provided with a plate cooperable with the outer end of said tubular member, a rod fixed relative to said casing and extending axially of said tubular member within the same and being cooperable with the receptacle supporting plate to prevent rotation thereof relative to the casing during axial move-

ment of the plate through said tubular member, and a stop cooperable with the receptacle supporting plate to limit axial movement of the receptacle assembly toward the casing.

5. A floodlight unit of the type described comprising a casing formed with an aperture in one side thereof, a tubular member arranged in the aperture of the casing and extending outwardly therefrom, a lamp receptacle assembly including a receptacle supporting plate adapted to be slidably moved through said tubular member, a lamp receptacle support depending from the under side of said plate, a lamp receptacle carried by said support, said support being adjustable to move the receptacle carried thereby toward and from said plate, a stem secured at one end to the upper side of said plate and extending axially through said member and being provided with a plate cooperable with the outer end of said tubular member, a rod fixed relative to said casing and extending axially of said tubular member within the same, said receptacle supporting plate being formed with a peripheral notch to slidably receive said rod, and a stop cooperable with the receptacle supporting plate to limit axial movement of the receptacle assembly toward the casing.

6. A floodlight unit of the type described comprising a casing formed with an aperture in one side thereof, a sleeve mounted on the casing in register with said aperture, a tubular member arranged in said sleeve and extending outwardly from the casing, said sleeve being adjustable to vary the angular relation between said tubular member and the axis of the casing, a receptacle assembly insertable through said tubular member and including a receptacle supporting plate adapted to be slidably moved through said tubular member, a receptacle mounted on the under side of said plate, a stem secured at one end to the upper side of said plate and extending axially through said tubular member and being provided with a plate cooperable with the outer end of said tubular member, said sleeve being provided with an inwardly extending flange adapted to support said receptacle supporting plate.

7. A floodlight unit of the type described comprising a casing formed with an aperture in one side thereof, a sleeve mounted on the casing in register with said aperture and being formed with a reflector supporting bracket depending in the casing, a tubular member arranged in said sleeve and extending outwardly from the casing, said sleeve being adjustable to vary the angular relation between said tubular member and the axis of the casing, a reflector carried by said bracket and being formed with an opening in one side thereof in register with said sleeve, a receptacle assembly including a receptacle supporting plate adapted to be slidably moved through said tubular member, a receptacle mounted on the under side of said plate and a lamp carried by the receptacle, said sleeve being formed with an inwardly extending flange forming a seat for the receptacle supporting plate to position the lamp carried by the receptacle in the focal axis of said reflector, a stem secured at one end to the upper side of the receptacle supporting plate and extending axially through said tubular member and being provided with a plate cooperable with the outer end of said tubular member.

ROYAL E. CROSSLEY.
